(57) **CLAIM**

The ornamental design for a tape measure housing, as shown and described.

DESCRIPTION

FIG. 1 is a perspective view of one embodiment of the tape measuring housing in accordance with the present invention.

FIG. 2 is a left view of the embodiment of FIG. 1.

FIG. 3 is a right view of the embodiment of FIG. 1.

FIG. 4 is a back view of the embodiment of FIG. 1.

FIG. 5 is a front view of the embodiment of FIG. 1.

FIG. 6 is a bottom view of the embodiment of FIG. 1.

FIG. 7 is a top view of the embodiment of FIG. 1.

FIG. 8 is a perspective view of another embodiment of the tape measure housing in accordance with the present invention.

FIG. 9 is a left view of the embodiment of FIG. 8.

FIG. 10 is a right view of the embodiment of FIG. 8.

FIG. 11 is a back view of the embodiment of FIG. 8.

FIG. 12 is a front view of the embodiment of FIG. 8.

FIG. 13 is a bottom view of the embodiment of FIG. 8; and, FIG. 14 is a top view of the embodiment of FIG. 8.

Throughout the FIGURES, aspects shown in broken lines are not considered a portion of the claimed ornamental design.
